UNITED STATES PATENT OFFICE.

JASPER L. WILLIAMS, OF PAWNEE, LOUISIANA, ASSIGNOR OF ONE-HALF TO THOMAS J. WILLIAMS, OF ROSEPINE, LOUISIANA.

DESIGN FOR A PIPE-WRENCH MEMBER.

SPECIFICATION forming part of Design No. 32,743, dated May 29, 1900.

Application filed April 27, 1900. Serial No. 14,632. Term of patent 3½ years.

To all whom it may concern:

Be it known that I, JASPER L. WILLIAMS, a citizen of the United States, residing at Pawnee, Calcasieu parish, State of Louisiana, 5 have invented and produced a new and original Design for a Pipe-Wrench Member, of which the following is a specification, reference being had to the accompanying drawings, forming a part of this specification.

10 Figure 1 is a side elevation of a pipe-wrench handle and shoe. Fig. 2 is a top plan view of the same.

15 As shown in the drawings, the leading or material feature of my design is a handle A, flattened at one end and curved upwardly, terminating in a hook-shaped end B. The curved or arc-shaped portion C is formed with teeth c upon its under side, projecting forward or outward tangentially to its arc. At

20 or near the juncture of the flattened portion and handle several depressions or channels a

are formed opposite one to the other on each side of the handle. At this point the handle is perforated and a swivel-bolt passed through or rigidly secured thereto.

25 It is apparent that this pipe-wrench member belongs to a class of chain pipe-wrenches, and is designed to be used with a chain which is fastened by one of its end links into the channels a or to the swivel-bolt, while the 30 hook-shaped end is designed to receive the link at the opposite end of the chain.

Having shown and described my invention, what I claim as new, and desire to secure by Letters Patent, is—

35 The design for a pipe-wrench member as herein shown and described.

In testimony whereof I affix my signature.

JASPER L. WILLIAMS.
